(57) **CLAIM**

The ornamental design for a shaving razor handle, as shown and described.

DESCRIPTION

FIG. 1 is a perspective view of a shaving razor handle showing my new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a perspective view of another embodiment of a shaving razor handle showing my new design;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

The broken lines are directed to the environmental subject matter and form no part of the claimed design. The smaller oval shape portion of the handle is shaded to represent the color black.
